FASTENER-APPLYING IMPLEMENT

Charles M. Lindstrom, East Greenwich, R. I., assignor to Boston Wire Stitcher Company, Warwick, R. I., a corporation of Maine

Application September 25, 1942, Serial No. 459,607

11 Claims. (Cl. 1—49)

The present invention relates to improvements in fastener-applying implements and more particularly to stapling or wire-stitching devices of the type having a pivoted gate for opening and closing the end of the staple-magazine.

One of the objects of the present invention is to provide an implement of the type indicated with means for positively locking the gate in closed position on the magazine.

Another object is to provide an implement of the type indicated in which the pivot-means for the gate operates to positively lock the gate in closed position on the magazine.

Another object is to provide an implement of the type indicated in which the pivot-means for the gate are in the form of push-buttons manually-operable to release the gate.

Another object is to provide an implement of the type indicated with detents for latching the gate in closed position on the magazine and pivot-means for positively locking the detents in latched engagement.

Another object is to provide an implement of the type indicated with axially-movable pivots having non-cylindrical portions for cooperation with correspondingly-shaped slots in the magazine and gate to positively lock the gate, and cylindrical portions for cooperation with the slots in the gate to release the latter for pivotal movement.

Still another object is to provide gate-locking means of simple and compact construction, automatically operable to lock the gate in closed position on the magazine and adapted to be quickly manipulated to release the gate.

Further objects of the improvement are set forth in the following specification which describes several forms of construction of the invention, by way of example, as illustrated by the accompanying drawing. In the drawing:

Fig. 1 is a side elevational view of a fastener-applying implement incorporating the novel features of the present invention and showing the gate latched against pivotal movement and locked against vertical sliding movement;

Fig. 2 is a transverse sectional detailed view on line 2—2 of Fig. 1 showing the pins for pivotally mounting the gate on the magazine and illustrating the detent-enlargements on the pins as in locking engagement with the openings or slots in the sides of the magazine;

Fig. 3 is a longitudinal sectional detailed view on line 3—3 of Fig. 1 showing the gate locked in its lowermost position to hold the recesses or

notches in its sides in engagement with the detent-lugs on the magazine;

Fig. 4 is a longitudinal sectional view through the front portion of the magazine showing the keyhole-form of the slots in the sides of the magazine and illustrating the gate as moved to its raised position to adapt it to be rocked on the pivot-pins;

Fig. 5 is a sectional view on line 5—5 of Fig. 4 showing the pivot-pins pressed inwardly toward each other to disengage the detents from the keyhole slots and aline the reduced shank-portions of the pins with the narrower portions of the slots;

Fig. 6 is a perspective view of the front end of the magazine and the parts of the gate-locking means in disassembled relationship;

Fig. 7 is a side elevational view of the forward end of the magazine showing a modified form of gate-locking means; and

Fig. 8 is a sectional view on line 8—8 of Fig. 7 showing the axially-movable pivot-pins as having rectangular portions for cooperation with correspondingly-shaped openings or slots in the magazine and gate to lock the latter in closed position on the magazine, and adjacent cylindrical portions to adapt the gate to pivot to open the magazine.

A certain type of fastener-applying implement is provided with a gate for normally closing the end of the magazine and rockable away therefrom to open the latter to receive a supply of fasteners. In one form of construction the gate is mounted on the magazine for pivotal and vertical sliding movement and is releasably latched in closed position by the engagement of detent-slots or notches in its bottom edges with detent-lugs on the magazine. A spring acting against the top of the gate is arranged to depress the latter to engage the notches in its bottom edges with the detent-lugs on the magazine and the gate may be opened by first lifting it vertically against the action of the spring to disengage the detents and then rocking the gate on its pivot. Such implements operate quite satisfactorily in most instances but on certain kinds of work the gate may become unlatched accidentally during operation of the implement. For instance, when a plier-type of tacker is used for attaching articles to a rough surface the operator may hold the implement inclined with respect to the work and drag the bottom edge of the gate against the rough surface of the work. Such use of the implement sometimes causes the gate to move

vertically against the action of the spring to thereby disengage the latching detents.

The present improvement is designed to prevent accidental or unwarranted unlocking of the gate and the invention relates generally to the provision of locking-means incorporated in pins for pivotally mounting the gate on the magazine. The pivot-pins are in the form of push-buttons and extend through alined openings or slots in the sides of the gate and the sides of the magazine and have detents engageable with the openings in at least one of the parts to positively lock the gate in closed position. In the preferred embodiment of the invention the gate is mounted for pivotal and vertical sliding movement and is provided with the usual cooperating notch-and-lug detents for latching the gate in closed position. A pair of pivot-pins are provided which extend through holes in the sides of the gate and through slots of keyhole-shape in the sides of the magazine, the pivot-pins being pressed axially outward by a compression spring positioned between their inner ends. The pivot-pins have conically-faced enlargements adjacent their inner ends which are engageable with the circular portions of the keyhole slots in the sides of the magazine to positively lock the gate against vertical sliding movement whereby to hold the detents in latched engagement. The gate may be released by pressing on the push-button extensions of the pins to cause the pins to be moved inwardly toward each other against the action of the spring to disengage their enlargements from the circular portions of the keyhole slots and aline the reduced shank-portions of the pins with the narrow portions of the slots. The gate then may be moved vertically to disengage the latched detents and rocked thereafter on the pivot-pins to open the magazine.

In a modified form of construction of the invention the latching detents are eliminated and the pivot-pins alone act to lock the gate in closed position on the magazine. In the modified form of construction the pivot-pins have non-circular portions which cooperate with correspondingly-shaped openings or slots in the sides of the magazine and the sides of the gate to lock the latter in closed position on the magazine. When the pivot-pins are pressed inwardly cylindrical portions adjacent the non-circular portions permit the gate to be rocked to open the magazine.

Referring to the drawing the invention is herein shown as applied to a stapling implement of the type illustrated and described in United States Letters Patent No. 2,137,642 to John F. Cavanagh issued November 22, 1938. It will be understood, however, that the present improvements may be applied to other types of fastener-applying implements having pivoted gates. Suffice it to state herein that the stapling implement comprises a hollow casing 2 adapted to rest against the work and mounting fastener-applying mechanism therein. The casing 2 has an opening 3 to provide for the insertion of the fingers therethrough and a hand-lever 4 pivotally mounted on the casing for actuating the fastener-applying mechanism whereby to adapt the implement to be held and operated in one hand.

Mounted on the bottom wall 5 of the casing 2 is a magazine comprising a channel-shaped member 6 having a bottom wall 7 and side walls 8 formed with inturned flanges 9 at their upper edges, see Figs. 1 and 6. Extending upwardly and forwardly from the inturned flanges 9 of the magazine are a pair of stanchions 10 and 11.

which overhang the end of the member 6. A pair of rails 12 extend longitudinally within the member 6 in spaced relation to the side walls 8, being attached to the bottom wall 7 by means of inwardly-directed lugs 13 welded or otherwise secured thereto, see Fig. 4. The longitudinally-extending rails 12 constitute a core, so-called, for supporting a plurality of fasteners, herein illustrated in the form of U-shaped staples S, arranged in straddled relationship thereon, the staples being held on the rails by the inturned flanges 9 which overlie their crossbars. The forward ends of the rails 12 extend beyond the forward end of the channel-shaped member 6 into an opening at the bottom of the casing 2 and underlie the stanchions 10 and 11. Depending from the side of the forwardly-extending end of each rail 12 is a laterally-offset flange 15, see Fig. 6, having a rearward shoulder engageable with the forward edges of the bottom walls 5 and 7 of the casing 2 and member 6, its lower edge alining with the bottom of the casing. The channel-shaped member 6 is attached to the casing 2 by means of screws 17 and 18 extending through the casing and the side walls 8 of the magazine. A U-shaped gate 19 for closing the front end of the magazine is mounted for rocking movement on the stanchions 10 and 11 in a manner later to be described in detail. The gate 19 has a front wall 20 and rearwardly and upwardly-extending side walls 21 and 22 which embrace the sides of the magazine-rails 12 and the sides of the stanchions 10 and 11.

The lower edges of the side walls 21 and 22 of the gate 19 have recesses or notches 26 therein which are engageable with detent-lugs 27 struck outwardly from the flanges 15 on the rails 12 of the magazine. With the gate 19 in closed position on the magazine and the notches 26 in engagement with the lugs 27 the front wall 20 of the gate is spaced from the forward ends of the rails 12 a distance equal to the thickness of a staple S to provide a throat 28 therebetween through which the staples are driven. The staples S are advanced along the rails 12 by a pusher 29 to position the foremost staple in the throat 28. The pusher 29 is advanced by a spring 30 having one end anchored to a lug on the bottom wall 7 of the channel-shaped member 6 and extending forwardly around a guide 31 with its opposite end connected to a lug depending from the pusher.

The staple-applying mechanism comprises a driver 35 attached to the end of a plunger 36 mounted for reciprocation in a guideway at the forward side of the casing 2. The plunger 36 is normally latched in raised position, as illustrated in Fig. 1, by a pivoted latch-member 37 and is adapted to be operated by a compression spring 38 when released by the latch. The spring 38 is compressed by rocking movement of the handle 4 which is connected to a lever 39 by a link 40. The lever 39 is pivoted at its rearward end to the casing 2 and is connected to the lower end of links 41 at the opposite sides of the spring 38, the upper ends of the links being fastened to a cross-pin 42 overlying a movable compression plate 43. The spring 38 is positioned between the compression plate 43 and the plunger 36 so that rocking movement of the handle 4 in counter-clockwise direction, as viewed in Fig. 1, will act through the link 40, lever 39 and links 41 to depress the plate 43 and compress the spring 38. At the end of the rocking movement of the handle-lever 4 an abutment or pin 44 for connecting

the link 40 to the lever 39 engages the latch-member 37 and rocks it in counterclockwise direction to release the plunger 36, which is then actuated by the compression spring 38 to slide the driver 35 through the throat 28. Upon release of the handle 4 a hairpin-spring 45 acting between the casing 2 and lever 39, see Fig. 1, is operable to return the parts to initial position and a similar type of spring 46 will return the latch 37 into engagement with the plunger 36. As thus far described, the implement is substantially identical with that illustrated and described in the Cavanagh patent referred to above.

In accordance with the present invention the means for pivotally mounting the gate 19 on the stanchions 10 and 11 of the magazine operate to positively lock the gate in closed position. In a preferred form of construction illustrated in Figs. 1 to 6, the pivot-means for the gate 19 operates to lock the gate against vertical sliding movement to retain its notches or recesses 26 in latched engagement with the lugs 27. The pivot-means comprises a pair of pins 47 and 48 of identical construction and of cylindrical form throughout the greater portion of their length with beveled or conical enlargements 49 adjacent one of their ends. The pin 47 extends through aligned openings 50 and 51 in the stanchion 10 and side wall 21 of the gate while the pin 48 extends through similar aligned openings in the stanchion 11 and side wall 22 of the gate. The openings 50 in the stanchions 10 and 11 are of keyhole form, see Fig. 6, having circular portions 52 at their lower ends and relatively narrow slots 53 extending vertically therefrom. The openings 51 in the side walls 21 and 22 of the gate 19 are of circular form and of such dimension as to adapt them to receive the cylindrical portions of the pins 47 and 48 with a close fit. A compression spring 58 is positioned between the inner ends of the pins 47 and 48 for normally urging them outwardly away from each other; the spring being supported and guided on centering bosses 59 at the ends of the pins. The pins 47 and 48 are of greater length than the combined thickness of the stanchion 10 or 11 and side wall 21 or 22 of the gate 19 to adapt their ends to project outwardly beyond the sides of the gate to provide manually-operable push-buttons 60 and 61. A preferred form of construction of the invention having been described in detail its mode of operation is explained as follows:

With the gate 19 latched in closed position by the engagement of its notches 26 with the lugs 27 and held against vertical sliding movement by the engagement of the enlargements 49 on the pivot-pins 47 and 48 with the rounded portions 52 of the keyhole slots 50 in the stanchions 10 and 11, see Fig. 1, the gate is positively locked against accidental or unwarranted opening. The implement may be operated to apply the staples S by depressing the handle-lever 4 which, acting through the link 40, lever 39, links 41 and compression plate 43 will compress the spring 38 until eventually the latch 37 is released from the plunger 36 by the engagement of the pin 44 therewith. Upon release of the latch 37 the spring 38 will actuate the plunger 36 carrying the driver 35 to slide the latter downwardly through the throat 28. A staple S positioned in the throat 28 thus will be driven into the work. Upon release of the handle 4 the spring 45 will act to rock the lever 39 in counterclockwise direction to return the parts to their initial positions, the spring 46 will return the latch 37 into engagement with

the plunger 36 and the spring-pressed pusher 29 will advance the foremost staple S into the throat 28. The operator may continue to operate the implement in this manner until the supply of staples S in the magazine is exhausted.

To reload the implement with a supply of staples S the operator must first unlock the gate 19 by simultaneously pressing the push-button extensions 60 and 61 of the pins 47 and 48 between the forefinger and thumb to slide the pins inwardly toward each other against the action of the spring 58, thereby shifting them from the position illustrated in Fig. 3 to that illustrated in Fig. 5. Such inward movement of the pins 47 and 48 will remove their conical enlargements or detents 49 from the circular portions 52 of the key-hole slots 50 in the stanchions 10 and 11 to release the gate 19 for vertical sliding movement. The gate 19 then may be slid vertically from the position illustrated in Fig. 1 to that illustrated in Fig. 4 to release the notches 26 in the sides 21 and 22 of the gate 19 from engagement with the lugs 27 on the rails 12; the cylindrical portions of the pins adjacent the conical enlargement moving in the reduced portions 53 of the keyhole slots 50 in the stanchions 10 and 11. Upon release of the notches 26 from the lugs 27 the gate 19 may be rocked to the position indicated by dash-lines in Fig. 4 to open the forward end of the magazine to receive a supply of staples S.

The staples S, preferably in the form of a self-sustained stick or refill are inserted into the magazine 6 in straddled relationship on the rails 12 of the core and the end of the magazine thereafter is closed by rocking the gate 19 back to the position illustrated in Figs. 4 and 5. The gate 19 is latched in closed position on the magazine by sliding it vertically downward to engage the notches 26 in the side walls 21 and 22 with the lugs 27 on the rails 12 whereby to prevent it from pivotal movement. The downward sliding movement of the gate 19 to latch it in closed position will carry the conical enlargement 49 on the pins 47 and 48 into position opposite the circular portions of the keyhole slots 50 and the spring 58 will then act to slide the pins to engage the enlargements 49 therewith. The gate 19 then will be held positively against vertical movement. It is to be noted that the beveled or conical shape of the enlargements 49 on the pins 47 and 48 is to insure their entrance into the circular portions 52 of the keyhole slots 50 even though the pins are not in exact axial alignment therewith. Thus the gate is locked positively in closed position on the front of the magazine. The implement is then ready to apply staples S in the manner explained above.

In Figs. 7 and 8 a modified form of construction of the invention is illustrated in which the latching notches 26 and detent-lugs 27 are eliminated and the gate positively locked in closed position on the magazine by its pivot-means. The gate 64 illustrated in Figs. 7 and 8 is similar to the gate 19 except for the notches 26 and has a front wall 65 and side walls 66 and 67. The gate 64 is mounted on stanchions 68 and 69, similar to the stanchions 10 and 11 previously described, by means of pins 70 and 71. The pins 70 and 71 are of identical form, each having a non-circular portion 72, herein illustrated as of rectangular or square contour, and an adjacent cylindrical portion 73. At the end of the square portions 72 each pin has a flange 74 which projects radially from the periphery of the pin. The

stanchions 68 and 69 and side walls 66 and 67 of the gate 64 have aligned apertures 75 and 76 of the same rectangular or square contour as the portions 72 of the pins 70 and 71. The pin 70 extends through the aligned square apertures 75 and 76 in the stanchion 68 and the side wall 66 of the gate 64 while the pin 71 extends through the square holes in the opposite stanchion 69 and side wall 67 of the gate. The pins 70 and 71 are normally pressed outwardly by a spring 77 to position their rectangular portions 72 in the aligned openings 75 and 76 in the stanchions 68 and 69 and sides 66 and 67 of the gate, the flanges 74 limiting the outward movement of the pins.

The arrangement of the rectangular holes 75 and 76 in the stanchions 68 and 69 and side walls 66 and 67 of the gate 64 are such as to properly position the front wall 65 of the gate in spaced relation to the end of the rails 12 to provide a throat 78 therebetween when the rectangular portions 72 of the pins 70 and 71 are positioned in the aligned openings. The rectangular portions 72 of the pins 70 and 71 also act to positively lock the gate against pivotal movement to hold it in closed position on the magazine. The outwardly-extending cylindrical portions 73 of the pins 70 and 71 constitute push-buttons to adapt the pins to be pressed inwardly toward each other against the action of the spring 77 to register their cylindrical portions with the rectangular openings in the side walls 66 and 67 of the gate 64. Thus the gate 64 will be released when the pins 70 and 71 are pressed inwardly toward each other to permit it to be rocked to the position indicated by dash-lines in Fig. 7 whereby to open the forward end of the magazine. The pins 70 and 71 thus operate to positively lock the gate 64 in closed position on the magazine but may be pressed inwardly between the forefinger and thumb to release the gate so that it may be opened to refill the magazine with a supply of staples.

It will be observed from the foregoing specification that the present invention provides for positively locking the gate in closed position on the magazine to prevent accidental or unintentional opening of the latter during operation of the implement. It also will be observed that the locking means of the present invention are of simple and compact construction to positively lock the gate in closed position while facilitating the release of the gate to open the magazine to receive a supply of fasteners.

While two forms of construction of the invention are herein illustrated and described, it is to be understood that further modifications may be made in the structure and arrangement of the gate-locking means without departing from the spirit or scope of the invention. Therefore, without limiting myself in this respect, I claim:

1. In a fastener-applying implement, a magazine for holding a supply of fasteners, a movable gate for opening and closing the magazine, said magazine and gate having aligned openings at opposite sides thereof, locking means comprising a pair of opposed push-button members extending through the aligned openings and having detents thereon, and a spring for normally urging the push-button members outwardly to engage their detents with at least one of the aligned openings in the magazine and gate at opposite sides thereof to positively lock the gate in closed position on the magazine, said push-button members being manually-operable against the action of the spring to disengage their detents from the open-

ings to release the gate whereby to permit it to be moved to open the magazine.

2. In a fastener-applying implement, a magazine for holding a supply of fasteners, a gate for opening and closing the magazine, a pin for pivotally mounting the gate on the magazine, locking means comprising cooperating detents on the pin and magazine for positively locking the gate in closed position, and a spring for normally urging the pin into locking position, said pin having a push-button extension to adapt it to be operated manually against the action of the spring for moving the detent to inoperative position to release the gate whereby to permit it to be moved to open the magazine.

3. In a fastener-applying implement, a magazine for holding a supply of fasteners, a gate for opening and closing the magazine, pins for pivotally mounting the gate on the magazine, locking means comprising cooperating detents on the pins and magazine for positively locking the gate in closed position, and a spring for normally urging the pins to locking position, said pins having push-button extensions to adapt them to be operated manually against the action of the spring for moving the detents to inoperative position to release the gate whereby to permit it to be moved to open the magazine.

4. In a fastener-applying implement, a magazine for holding a supply of fasteners, a gate mounted on the magazine for pivotal and vertical sliding movement, means for latching said gate against pivotal movement on the magazine, and means for locking the gate against vertical sliding movement on the magazine, said locking means having a push-button extension for manual operation to release the gate whereby to permit it to be moved to open the magazine.

5. In a fastener-applying implement, a magazine for holding a supply of fasteners, a gate mounted on the magazine for pivotal and vertical sliding movement, means for latching said gate against pivotal movement on the magazine, means for locking the gate against vertical sliding movement on the magazine, and a spring for normally urging the locking means into operative position to positively lock the gate closed on the magazine, said locking means having a push-button extension for manual operation to release the gate whereby to permit it to be moved to open the magazine.

6. In a fastener-applying implement, a magazine for holding a supply of fasteners, a gate mounted on the magazine for pivotal and vertical sliding movement, cooperating detents on the magazine and gate engageable upon vertical sliding movement of the latter to latch the gate in closed position on the magazine, means for locking the gate against vertical sliding movement, and a spring for normally urging the locking means into locking position, said locking means having a push-button extension for manual operation to release the gate whereby to permit it to be moved to open the magazine.

7. In a fastener-applying implement, a magazine for holding a supply of fasteners, a gate for opening and closing the magazine, a pin for pivotally mounting the gate on the magazine, said magazine having a keyhole slot through which the pin extends, means for latching the gate in closed position on the magazine by sliding the gate vertically thereon, locking means comprising a detent on the pin engageable with the keyhole slot in the magazine for positively locking the gate in closed position, and a spring

for sliding the pin to engage the detent with the keyhole slot, said pin having a push-button extension for operation manually to move the pin and detent axially to release the gate whereby to permit it to be swung to open the magazine.

8. In a fastener-applying implement, a magazine for holding a supply of fasteners, said magazine having keyhole slots at the sides thereof adjacent its forward end, a gate for opening and closing the magazine having holes in its sides in alignment with the keyhole slots in the magazine, pins extending through the holes and keyhole slots in the sides of the gate and magazine for pivotally mounting the gate on the magazine, cooperating detents on the magazine and gate engageable upon vertical sliding movement of the latter to latch the gate in closed position on the magazine, locking means comprising enlargements on the pins engageable with the keyhole slots in the sides of the magazine for positively locking the gate against vertical sliding movement, and a spring for normally urging the pins into locking position, said pins having push-button extensions to adapt them to be moved axially against the action of the spring to release the gate whereby to permit it to be moved to open the magazine.

9. In a fastener-applying implement, a magazine for holding a supply of fasteners, a gate for opening and closing the magazine, said gate and magazine having aligned apertures of non-circular shape, and a pin extending through the aligned apertures in the gate and magazine and having a non-cylindrical portion corresponding to the shape of the apertures and an adjacent cylindrical portion, said non-cylindrical portion of the pin normally being positioned in the apertures in the gate and magazine to lock the gate

in closed position and said pin being manually-movable axially thereof to position its cylindrical portion in the aperture in the gate whereby to permit the gate to be rocked to open the magazine.

10. In a fastener-applying implement, a magazine for holding a supply of fasteners, a gate for opening and closing the magazine, said gate and magazine having aligned apertures of non-circular shape, a pin extending through the aligned apertures in the gate and magazine, said pin having a non-cylindrical portion corresponding to the shape of the apertures and an adjacent cylindrical portion, and a spring for normally urging the pin to engage its non-cylindrical portion with the apertures in the gate and magazine to positively lock the gate in closed position on the magazine, said pin having a push-button extension for manually moving the pin axially to position its cylindrical portion in the aperture in the gate whereby to permit the gate to be rocked to open the magazine.

11. In a fastener-applying implement, a magazine for holding a supply of fasteners, a gate for opening and closing the magazine, the sides of the gate and the magazine having aligned rectangular openings, pins in the aligned openings having rectangular portions and adjacent cylindrical portions, and a spring acting between the pins to position the rectangular portions in the aligned openings to positively lock the gate in closed position on the magazine, said pins having push-button extensions manually-operable against the action of the spring to align their cylindrical portions with the apertures in the gate whereby to permit it to be rocked to open the magazine.

CHARLES M. LINDSTROM.
